FREQUENCY MODULATED OSCILLATOR
CONTROLRichard H. Ranger, United States Army,
Newark, N. J.

Application July 6, 1944, Serial No. 543,746

10 Claims. (Cl. 250—36)

(Granted under the act of March 3, 1883, as
amended April 30, 1928; 370 O. G. 757)

1

The invention described herein may be manufactured and used by or for the Government for governmental purposes, without the payment of any royalty thereon.

In the case of oscillators working at very high frequencies (VHF) a small percentage change in the frequency output amounts to a very large numerical change in frequency. The means provided to hold the output frequency of the oscillator constant must be able to handle this possibly large variation in frequency.

One object of this invention is to provide a control which uses frequency modulation for holding the output of VHF oscillator substantially constant at a selected frequency.

Another object of this invention is to provide means which operate to restore a controlled oscillator to a preselected frequency, this operation being performed with increasing discrimination as the oscillator approaches that frequency.

Yet a further object of this invention is to provide a control means having, as a part thereof, a frequency modulated mechanism in which the intensity of the frequency modulation is decreased, as an oscillator under the control of said means approaches the desired frequency at which it is to be maintained.

Other objects of this invention will be set forth hereinafter, or will be obvious as the description proceeds.

For a further exhibition of my invention reference may be had to the annexed drawings and specification at the end whereof, the novel features of my invention will be specifically pointed out and claimed.

Figure 1 of the drawings is a block diagram in which the various parts are marked with appropriate legends.

Figure 2 is a diagram illustrating the mode of operation of this device.

But one embodiment of my invention has been selected for description as numerous modifications will be readily apparent to those skilled in this art. In this embodiment, block 1 represents a crystal-controlled oscillator of a convenient frequency, for example, 1 megacycle (mc.). There is also provided a second oscillator 2 which may conveniently have an output frequency of 1 kilocycle (kc.). A portion of the output of oscillator 2 is fed through a gain control circuit 3 to a phase shift modulation circuit 4, which is arranged so that the output of oscillator 2 shifts the phase of the frequency put out by crystal 1. As is well known in the art, on multiplying the phase shifted output, frequency modulation may

2

be accomplished. The frequency modulation circuit 4 contains an amplifying tube biased to give a very distorted output. This output will then be very rich in harmonics. The frequency modulated output from circuit 4 is fed to harmonic amplifier circuit 5, and a harmonic selector circuit 6 which provides means for selecting a desired harmonic of the frequency modulated output of circuit 4.

- 10 The oscillator whose frequency is to be controlled is shown at 7. It contains adjustment 8 shown as a capacitor although an inductor might well be used. Adjustment 8 is connected in parallel with the larger normal circuit element 9.
- 15 The outputs of oscillator 7 and harmonic selector 6 are fed to a mixer-detector circuit 10, which in conventional fashion, provides in its output a beat note having a frequency which is equal to the difference between the frequencies 20 of the outputs of oscillator 7 and harmonic selector 6, respectively. However, as will be explained in more detail below, this beat note frequency is variable since the frequency of the output of harmonic selector 6 is itself variable. For 25 convenience, this variable beat note will be called the primary beat. Output of mixer-detector 10 is fed to a detector or frequency-modulation discriminator circuit 12. In the conventional manner, the discriminator circuit converts the 30 variations of frequency of the output of mixer-detector 10 into variations of amplitude at a constant frequency, which may, for convenience, be called the secondary beat. The discriminator circuit is so designed that this secondary beat has 35 the same frequency as that of oscillator 2, e. g., 1 kc.

Let it be assumed that the harmonic frequency selected is at f_1 as shown in Figure 2. The modulation energy oscillator 2 is then connected 40 through gain control 3 to shift the phase at 4 (Figure 1), and, in consequence, the selected harmonic 6 shifts back and forth from f_1 to f_2 as indicated above the modulation energy trace. 45 As is shown here, connections are assumed to be such that a positive swing of the modulation energy will cause an increase in the frequency of the harmonic selected. A decrease in the frequency of the harmonic selected is caused by a corresponding negative swing of the modulation energy.

Now, if the controlled frequency is above the selected harmonic, as indicated at f_3 , it is obvious that the primary beat between them will be lower when the harmonic is swung to f_2 than it will be when the harmonic is swung to f_1 . In other

words, the ensuing primary beat will be inversely proportional in frequency to the modulation energy if the frequency to be controlled is above the harmonic selected as it is as shown at f_3 .

Contrarywise, if the frequency to be controlled is below the selected harmonic as shown at f_4 the primary beat will be proportional in frequency to the modulation energy swing, as excursions of the selected harmonic to the right at f_2 will increase the frequency of the beat between it and the oscillator at f_4 .

It is now necessary to have a discriminator which will indicate these frequency changes in the primary beat. This is accomplished in the discriminator 12 (Figure 1). As is well known in the art, it is easy to arrange such a discriminator circuit. For example, a capacitive coupling in any of the amplifier stages would give an increased output for increased frequency, whereas an inductively reactance coupling would give a decreasing energy response for increasing frequencies.

Let it be assumed that a capacitive coupling is used which will give an increasing response for increasing beat frequency.

The output of the discriminator 12 will, as stated above, be the same as that caused by the modulation energy of oscillator 2. The beat note pattern of the output of mixer-detector 10 will be the same, for a certain variation of the frequency of controlled oscillator 7 in an upward direction, as the beat note pattern for the same variation in a downward direction. The two beat note patterns will, however be 180° out of phase with each other. One of these beat note patterns would be in phase with the output of oscillator 2 while the other would be 180° out of phase with this output. As has already been stated, discriminator 12 converts the variable beat note frequency output of mixer-detector 10 into a constant frequency. In addition, discriminator 12 operates in conventional fashion to recognize the phase of its input. Accordingly, with one beat note pattern, it produces a first output with one phase relation which may be assumed to be in phase with the output of oscillator 2, while with the other beat note pattern the output of discriminator 12 is 180° out of phase with the first output and therefore 180° out of phase with the output of oscillator 2.

By means of the 90 degree phase shift 15, the output of the oscillator 2 is assumed shifted forward 90 degrees to act as a reference frequency in one set of coils of a two-phase motor 13. This two-phase motor 13 will then rotate in one direction or the other when the output of 12 is also applied to its other set of coils, depending upon the existing phase relationship of the output of 12 and the oscillator 2.

The net result is that the two-phase motor 13 will rotate in one direction or the other as the phase of the secondary beat reverses, depending upon whether the controlled frequency put out by oscillator 7 is above or below the selected harmonic. Thus, it is only necessary to have motor 13 drive adjustment 8 (in this case a trimmer capacitor) in such a direction that an in-phase secondary beat will move the motor in a direction to decrease the trimmer capacitance, whereas an out-of-phase secondary beat will cause motion in the opposite direction and increase the trimmer capacitance across that of the main tuning capacitor 9 of the controlled oscillator 7.

When the frequency of the controlled oscillator 7 centers at the average of the frequency modu-

lated position of the selected harmonic then the secondary beat will be at double the modulation frequency, and therefore there will be practically no secondary beat at the modulated frequency, and the correction motor will come to rest.

In order to provide a control for a wide band of frequencies and at the same time to provide motor 13 with sufficient power as the controlled oscillator 7 approaches the frequency for which it is set, an automatic volume control circuit 16 is provided. This circuit works in two ways, both of which depend upon the decrease in frequency of the primary beat.

Due to the capacity coupling 11 between the primary beat output from mixer-detector 10 to the automatic volume control 16, the energy transfer will decrease as the primary beat decreases in frequency. This decrease is reflected in automatic volume control 16 to decrease the phase shift gain control 3, so that the final frequency shift in the output of harmonic selector 6 will decrease as the primary beat decreases, which comes about as the oscillator 2 is approaching the right frequency. But by the same token, the power of the secondary beat output from the discriminator 12 would likewise decrease. To compensate for this, the decreasing energy entering automatic volume control 16 is made to increase the gain inversely in the discriminator 12. The purpose of this coupling to the automatic volume control at 16 is to see to it that as the primary frequency beat decreases in intensity that there is a corresponding automatic volume control in 16 which will decrease the gain in 3 and conversely increase the gain in 12. It is, of course, obviously possible to reverse the effective control on 12 and 3 of the automatic volume control 16, one down and the other up, as is well known in the art.

The arrows in all the circuit connections of the drawings show the way in which the action progresses.

I claim:

1. A process of controlling the frequency of a high frequency oscillator over a wide range of frequencies, said process comprising, generating a first electrical wave of substantially constant frequency, generating a second electrical wave of substantially constant frequency, shifting the phase of said first wave by modulating the frequency of said first wave by means of said second wave, amplifying and selecting a harmonic of said phase-shifted wave, generating a third electrical wave whose frequency is to be controlled, mixing said amplified and selected harmonic with said third wave and thus detecting a primary beat note of variable frequency, converting the primary beat note into a secondary beat note of the same frequency as the second wave, and combining energy from the secondary beat note and from the second wave in phase quadrature to each other to provide control energy to cause the frequency of the third wave to be brought to its proper frequency in the event of any variation from such proper frequency.

2. A process of controlling the frequency of a high frequency oscillator over a wide range of frequencies, said process comprising, generating a first electrical wave of substantially constant frequency, generating a second electrical wave of substantially constant frequency, shifting the phase of the said first wave by modulating the frequency of said first wave by means of said second wave, generating a third electrical wave whose frequency is to be controlled, mixing said third wave and said frequency-shifted wave, thus

detecting a primary beat note of variable frequency, converting the primary beat note into a secondary beat note of the same frequency as the second wave, and combining energy from the secondary beat note and from the second wave in phase quadrature to each other to provide control energy to cause the frequency of the third wave to be brought to its proper frequency in the event of any variation from such proper frequency and causing said second wave to vary the modulation intensity of said frequency modulation in direct ratio to the difference in frequency between said third wave and said frequency-shifted wave.

3. A process of controlling the frequency of a high frequency oscillator over a wide range of frequencies, said process comprising, generating a first electrical wave of substantially constant frequency, generating a second electrical wave of substantially constant frequency, shifting the phase of the said first wave by modulating the frequency of said first wave by means of said second wave, generating a third electrical wave whose frequency is to be controlled, mixing said third wave and said frequency-shifted wave, thus detecting a primary beat note of variable frequency, converting the primary beat note into a secondary beat note of the same frequency as the second wave, and combining energy from the secondary beat note and from the second wave in phase quadrature to each other to provide control energy to cause the frequency of the third wave to be brought to its proper frequency in the event of any variation from such proper frequency and compensating for the tendency of the intensity of the secondary beat note to decrease as the frequency difference between said third wave and said frequency-shifted wave decreases.

4. A process of controlling the frequency of an oscillator, comprising: generating a first electrical wave of substantially constant frequency, generating a second electrical wave of substantially constant frequency, frequency-modulating the first wave by means of the second wave, generating a third electrical wave whose frequency is to be controlled at a certain normal value, mixing the third wave and the frequency-modulated wave and thus detecting a primary beat note of variable frequency, converting the primary beat note into a secondary beat note of the same frequency as the second wave, and combining energy from the secondary beat note and from the second wave in phase quadrature to each other to provide control energy to bring the frequency of the third wave to its normal value in the event of its variation from such normal value.

5. An electrical frequency control system comprising: a reference oscillator circuit, including frequency-modulating means, for producing a frequency-modulated output having a predetermined mean frequency; a controlled oscillator circuit whose frequency normally has a predetermined constant value and which includes tuning means; mixer-detector means whose input is derived from the reference oscillator circuit and from the controlled oscillator circuit, and whose output has a beat frequency which is equal to the difference between the frequencies of its respective inputs; discriminator means whose input is derived from the output of the mixer-detector means and whose output has a constant frequency; and frequency-adjusting means deriving input from the discriminator means and from the frequency-modulating means and thus being

responsive to a variation of the controlled frequency from its normal value, such frequency-adjusting means being connected to the tuning means and operating the tuning means to bring the controlled frequency to its normal value, in the event of its variation from such normal value.

6. Means for controlling the frequency of an oscillator comprising: reference oscillator means, such means including a reference oscillator and including also frequency-modulating means which convert output of the reference oscillator into frequency-modulated energy with a predetermined mean frequency value, such frequency-modulating means comprising modulating oscillator means having a predetermined constant frequency; controlled oscillator means whose frequency normally has a predetermined constant value and which include tuning means; mixing-detector means supplied with energy from the reference oscillator means and the controlled oscillator means, and producing an output with a beat frequency equal to the difference between the frequencies of the energy from the reference oscillator means and the controlled oscillator means, respectively; discriminator means supplied with energy from the mixer-detector means and having a constant frequency output; and motor means which derive input from the modulating oscillator means and the discriminator means, respectively, and which combine the respective inputs in phase quadrature to each other, such motor means being connected to and serving to operate the tuning means to bring the controlled frequency to its normal value, in the event of its variation from such normal value.

7. Means for controlling the frequency of an oscillator, as described in claim 6, in which the frequency-modulating means include phase-shifting means deriving input from the reference oscillator and the modulating oscillator means, and include also means for amplifying and selecting a harmonic of the output of these phase-shifting means.

8. Means for controlling the frequency of an oscillator, as described in claim 6, which include automatic volume control means deriving input from the mixer-detector means and supplying energy to the modulating oscillator means to cause the frequency deviation of the output of the reference oscillator means to become progressively smaller as the extent of the variation of the controlled frequency from its normal value becomes smaller.

9. Means for controlling the frequency of an oscillator, as described in claim 6, which include automatic volume control means deriving input from the mixer-detector means and supplying energy to the discriminator means in such manner as to compensate for the tendency of the output of the discriminator means to decrease with decrease in the output of the mixer-detector means, as the extent of the variation of the controlled frequency from its normal value becomes smaller.

10. Means for controlling the frequency of an oscillator, as described in claim 6, which include automatic volume control means deriving input from the mixer-detector means and supplying energy to the modulating oscillator means to cause the frequency deviation of the output of the reference oscillator means to become progressively smaller as the extent of the variation of the controlled frequency from its normal value becomes smaller; such automatic volume control means also concurrently supplying energy to the

discriminator means in such manner as to compensate for the tendency of the output of the discriminator means to decrease with decrease in the output of the mixer-detector means, as the controlled frequency approaches its normal value. 5 RICHARD H. RANGER.
